UNITED STATES PATENT OFFICE

100,562

DESIGN FOR A PLAYGROUND CLIMBING APPARATUS

Archibald B. Horne, Brooklyn, N. Y.

Application July 20, 1933, Serial No. 48,761

Term of patent 14 years

To all whom it may concern:

Be it known that I, Archibald B. Horne, a citizen of the United States, residing at Brooklyn, in the county of Kings and State of New York, have invented a new, original, and ornamental Design for a Playground Climbing Apparatus, of which the following is a specification, reference being had to the accompanying drawing, forming part thereof.

The figure is a perspective view of a playground climbing apparatus, showing my new design.

I claim:

The ornamental design for a playground climbing apparatus, as shown.

ARCHIBALD B. HORNE.
